SPRAY GUN UNIT

Bronislaw Zapolski, Hastings on Hudson, N.Y., assignor
to Union Carbide Corporation, a corporation of New
York

Application July 22, 1958, Serial No. 51,888

Term of patent 14 years

(Cl. D62—2)

The figure is a perspective view showing the top, front and one side of a spray gun unit embodying my design; the other side is substantially the same, and the back is substantially plain. The nozzle and containers are shown in broken lines for illustrative purposes only.

I claim:

The ornamental design for a spray gun unit, as shown and described.
